Bro. Smith

ATTORNEY

position shown in Figures 8, 9, 10 and 11, while the fingers 37 maintains the awning in position relative to the window and the guideways 28 when the awning is in the position illustrated in Figure 4. By simply compressing the sides of the awning slightly these fingers may be inserted within the grooves of the guideways 28 or removed therefrom.

I do not wish to be limited to the exact mechanical form as illustrated, as other mechanical equivalents may be substituted still carrying out the objects of my invention.

What I claim is:

1. An awning construction comprising an awning frame, a vertically adjustable slidable mount for adjustably supporting said awning, guide ways for said mount and having means for attachment to a window frame, means for centrally pivoting the awning to the slidable mount to accommodate angular turning of the awning, and lateral connections on the ends of said awning for cooperating with the guideways on the window frame when the awning is in a vertical or a horizontal position.

2. An awning construction for window frames, comprising a pair of vertical guide ways attached to the window frames, a horizontal bar slidably mounted in said guideways, an awning frame pivotally mounted on said horizontal bar to adjust

5 said awning frame in either a horizontal or vertical position, fingers on the bottom corners of the awning frame to engage the guideways when the awning frame is in a vertical or horizontal position, and means for raising and lowering the horizontal bar and awning frame when in either a horizontal or vertical position.

3. In an awning construction, an awning mounting including a bar, an awning frame centrally pivoted to the bar whereby the awning frame can be adjusted to a vertical or horizontal position, means for guiding the vertical movement when in either vertically or horizontally positioned, and means for vertically adjusting the awning frame.

MERLE V. RING.
